FIG-1

FIG-2

FIG-3

FIG-4

Fig. 1 is a perspective view of a check out counter embodying my new design as seen from the customer's side; Fig. 2 is a perspective view of the opposite side thereof;

Fig. 3 is a top plan view of Fig. 2; and

Fig. 4 is an end elevational view taken from the right of Fig. 1.

The design is characterized by a top surface lying substantially in a single horizontal plane comprising an elongated rectangular portion extending tangentially from the circumference of a circular portion and a generally wedge-shaped block overlying a portion of said rectangu-

lar portion and of said circular portion at the point of tangency as shown.

I claim:

The ornamental design for a check out counter, substantially as shown and described.
